G. Smith. H. C. Brown. & J. A. Read, of Philadelphia Pa:
Assignors to
Leibhardt, McDonell & Co. of the same place
Letters Patent No 956. Dated Oct. 13th 1857

~~~~~  
The schedule referred to in these Letters Patent & making part of the same.  
~~~~~

To all whom it may concern:

Be it known, that we Garrison

2

Des. 976

Smith, Henry Brown, and Joseph A. Read, all of the city of Philadelphia and state of Pennsylvania have invented or produced a new and original design for a cooking stove and we do hereby declare that the accompanying drawing is a full, clear, and exact representation of the same.

Fig. 1. is a plan view of the bottom plate of the stove

Fig. 2. a plan of the top plate.

Fig. 3. an elevation of one of the side plates with doors, of the stove, both sides being alike...

Fig. 4. a front view with doors, and,

Fig. 5. a back view.

We claim the ornamented plates and doors as combining to form an ornamental cook stove.

In testimony whereof we have signed our names to this specification before two subscribing witnesses.
